DESIGN FOR A STEAK TONG

Admiral D. Warner, Longview, Wash.

Application December 9, 1946, Serial No. 135,356

Term of patent 7 years

(Cl. D44—4)

To all whom it may concern:

Be it known that I, Admiral D. Warner, a citizen of the United States, residing at Longview, in the county of Cowlitz and State of Washington, have invented a new, original, and ornamental Design for Steak Tongs, of which the following is a specification, reference being had to the accompanying drawing, forming part thereof.

I claim:

The ornamental design for a steak tong, as shown.

ADMIRAL D. WARNER.
